CLAIM

I claim the ornamental design for a seating unit, as shown and described.

DESCRIPTION

FIG. 1 is a perspective view of a seating unit showing my new design.

FIG. 2 is a right side view of FIG. 1, the left side being a mirror image thereof;

FIG. 3 is a front elevation view thereof;

FIG. 4 is a rear elevation view thereof; and,

FIG. 5 is a top plan view thereof.

The broken lines shown in FIGS. 1-5 are for illustrative purposes only and form no part of the claimed design.
